Attorneys.

UNITED STATES PATENT OFFICE.

ALLAN E. LARD, OF WASHINGTON, DISTRICT OF COLUMBIA, ASSIGNOR TO THE METALLIC SHAFT COMPANY, OF WILMINGTON, DELAWARE, A CORPORATION OF DELAWARE.

GOLF SHAFT.

Application filed December 14, 1922. Serial No. 606,981.

To all whom it may concern:

Be it known that I, ALLAN E. LARD, a citizen of the United States, residing at Washington, District of Columbia, have invented certain new and useful Improvements in Golf Shafts, of which the following is a specification.

This invention pertains to shafts for golf clubs and the main object of the invention is to produce a strong, durable, inexpensive metallic shaft that will duplicate the torsion, flexibility, weight, "feel" and "balance" of a first class hickory shaft. The scarcity of first class hickory has rendered a steel substitute an imperative necessity. Steel golf shafts as commonly made in the form of a plain tapered tube lack the "feel" and torsion of hickory, and it is conceded by the masters and students of the game that this torsional element is a fundamental necessity with respect to both the pleasure and execution of a correct golf stroke. Lack of torsion likewise decreases the driving power of the shaft.

Stated in general terms, the shaft which forms the basis of the present invention may be said to comprise a tapered tube formed from thin sheet high carbon steel, the tube having a groove, or series of grooves, extending longitudinally thereof, said groove or grooves causing the shaft to torsion under stress of the shot.

Several embodiments of the invention are illustrated in the annexed drawings, wherein,

Fig. 1 is a perspective view, in sections, of a finished shaft, broken away in part to more clearly illustrate the construction. The head and leather grip are only partially shown;

Fig. 2 a similar view showing the stepped overlap and locking means of a partially formed tapering tube;

Fig. 3 a perspective view of a punched strip of copper alloy or other suitable material which is placed between the overlapping surfaces of the tube, and which is employed, as hereinafter mentioned, to produce a strong and flexible union between the parts;

Fig. 4 is a like view illustrating a modified form of the openings punched in such strip;

Fig. 5 a perspective view, broken away in sections, showing the progressive stages of securing the overlap;

Fig. 6 is a sectional view on the line VI—VI of Fig. 5, of a portion of the shaft, on an enlarged scale;

Fig. 7 a transverse sectional view of the completed shaft, the line of section being adjacent the upper end;

Fig. 8 a like view at the lower end of the shaft;

Fig. 9 a sectional elevation of the upper end of the shaft, illustrating filler pieces in the upper ends of the grooves, employed to prevent lateral movement in the circumferential segments when the stress, incident to use, is applied to the handle;

Fig. 10 a perspective view of a slightly modified form of locking means formed in the surface of the overlap;

Fig. 11 a perspective view of a portion of the upper end of a modified form of shaft wherein the grip portion of the shaft is formed as an integral section of the shaft; and

Fig. 12 a transverse sectional view of a shaft with one groove, the edges of said groove having been brought together in cylindrical forming dies.

Referring first to Figs. 1 to 9 inclusive, 1 denotes the body of the shaft which is formed from a sheet of high carbon steel approximately .012" in thickness. The sheet is so cut that, when bent to form, it will produce a tube gradually tapering from its upper to its lower end. Along one edge there is formed a step or depressed section 2, from the outer edges of which there extends a series of lugs or fingers 3, preferably spaced about one inch apart, and adapted, when bent upwardly, to extend through openings 4 formed in a very thin copper alloy strip 5, and through openings 6 formed adjacent the outer edge of the tubular body, said openings being so punched as to produce a taper and thereby lock the upset fingers. A strip, such as shown in Fig. 4, will, however, be preferably employed in place of that shown in Fig. 3, the openings in the strip being made by a punching operation which produces flanged edges or tube-like projections 4a which surround the fingers 3 and extend up into the slots or openings 6 when the parts are assembled, thus placing a thin layer of copper alloy between the fingers and the walls of the openings.

100 In assembling, the copper alloy strip is placed upon the depressed portion 2, the upturned 105 fingers 3 being inserted through the openings 4, and the strip being bent upwardly so as to bring the flanged edges 4a into the slots 6. The tube 1 is then bent 110 so as to form the shaft, the fingers 3 being bent upwardly so as to grip the outer edge of the tube 1.

2 fingers 3 being passed through the openings 4^a and through openings 6, it being understood that the form of openings 4^a is preferred rather than the plain openings 4. The 5 ends of the fingers are now turned down, as shown in the lower portion of Fig. 5, thus drawing the parts close together and in perfect alinement. It will now be noted that a layer of copper alloy is interposed between 10 all steel surfaces, thus insuring the best possible braze. A mandrel is now inserted in the tube and the same is subjected to the compression of the forming dies, thereby bringing the various elements into 15 the closest possible contact and securing them in this relation by the upsetting and clinching of the ends of the fingers 3. A very close contact and a very neat fit are essential to a perfectly brazed union. The 20 parts prior to assembling, should be thoroughly cleaned to further insure a sound braze.

25 The tubular member when thus formed is brazed in a hydrogen or non-oxidizing atmosphere. As this process of joining two pieces of steel having copper interposed between their surfaces is old and well known, a detailed description is not deemed necessary. After the brazing operation the 30 fingers are ground off flush, when it will be found that the upsetting has formed wedge-shaped locking members out of the short stem or base of the fingers, thus forming, in conjunction with the braze, a tubular 35 member of great strength.

40 The diameter of the tapered tubular member thus produced is approximately .850" at upper and .640" at lower end and the length is about 37". It is then subjected to the action of a plurality of dies which simultaneously form a plurality of grooves extending longitudinally of the shaft and preferably equally spaced about the axis thereof. Three grooves will preferably be 45 produced and the grooves, which are denoted by 8, will preferably be made somewhat deeper toward the upper end of the shaft than they are at the lower end, or, in other words, the grooves will gradually 50 taper from the maximum depth at the upper end to a somewhat lesser depth at the lower end. Thus, as will be seen upon reference to Figs. 7 and 8, the grooves, while being deeper at the upper end of the shaft will 55 not so closely approach each other at their rounded bottoms as they do at the lower end of the shaft, as depicted in Fig. 8. These grooves cause the shaft to torsion when the club head impacts with the ball 60 and a very perceptible torsion is even noticeable when the head is twister by hand. The grooves add greatly to the shock resisting power of the shaft, in addition to imparting the feature of torsion. Forming the 65 grooves, of course, reduces the diameter of

the tubular member, and when three are formed this member is reduced from the diameters given above to approximately the following dimensions for the grooved body of the shaft, viz:— $\frac{3}{2}$ " at upper and $\frac{1}{2}$ " at 70 lower end. A greater or less number of grooves can, of course, be employed, but I prefer three because that number brings the complete shaft, including the handle, within the required weight (approximately 75 $5\frac{1}{2}$ oz.) and makes it equally flexible on all sides. If less than three grooves are employed the flexure is not uniform, and if more than three are present the shaft will be overweight as the presence of more 80 grooves will necessitate the use of a tube of larger initial diameter. Sheet material thinner than .012" develops weakness and too much flexibility, hence the weight in such larger tube, to accommodate the production of four or more grooves, can not be successfully reduced by reducing the thickness of the sheet metal. Correct weight, proper and uniform flexure in all directions, are found in first class hickory shafts, and 85 it is the object of this invention to exactly 90 reproduce in steel, this class of hickory shaft.

95 In the form of shaft shown in Fig. 1, which is the preferred form, the upper portion for a length of about 6 or 7 inches, is formed of a separate member 9. This member, which I term a "handle" is formed of a separate piece of round tubing, without grooves, but having, preferably, the same locked overlap and joined in the same 100 manner as the body of the shaft. The lower end of the handle 9 will be preferably given a slightly outward taper toward its lower end, while the upper end of the shaft will be given a slightly inward taper, as best 105 shown in Figs. 1 and 9, in order that the parts may be readily assembled and a tight driving fit effected as the handle is driven home, the seam in the handle registering with a 110 groove in the shaft. The contacting surfaces will be shellaced and pinned. In order to secure the outer segments of the shaft against lateral movement at the extreme end, under stress applied to the handle, I provide a small filler piece, say of aluminum, as 115 indicated at 10, Fig. 9, said filler piece being driven into each of the grooves at the upper end.

120 A suitable filler may be placed within the grooves and dressed off, as indicated at 11, Fig. 1. In this instance it is a cotton or leather string which is forced into the grooves and anchored by a suitable waterproof adhesive with which it is covered prior to its being pressed into the grooves.

125 In Fig. 10 is shown a slight modification of the form of interlock between the overlap prior to brazing. In this instance, instead of having fingers extending outwardly from the sheet from which the tube is formed, ears 130

12 are struck up from the depressed edge of the sheet.

In Fig. 11 a further modification is shown, wherein instead of employing a separate member, as 9, to produce the handle, the blank from which the shaft is formed, is made longer so that the handle section, denoted by 13, is formed as an integral portion of the shaft. The grooves begin to decrease in depth about 10 inches from the upper end and fade away to nothing adjacent the end which now becomes cylindrical in cross section. The separate handle construction is, however, preferable. It is lighter and the overlapping of the handle and shaft stiffens the shaft under the grip, and torsion at the extreme upper end of the shaft is not required. Furthermore, the body of the shaft being correspondingly shorter, develops less distortion in the quenching incident to the heat treatment. It is a very difficult and expensive operation to straighten high carbon, thin walled shafts that have become badly warped or distorted in the quenching, that is, straighten them without prohibitive loss in breakage and impairment to the structure of the steel.

It is understood that the degree or amount of torsion is governed or regulated by the depth and width of the grooves, the deeper and narrower the grooves, the more torsion the shaft will develop. In order to obtain the required torsion it is necessary to make the grooves quite deep, as will be readily seen by reference to Figs. 7 and 8. In the shafts which I have made and actually played golf with, I preferably formed the grooves, as above mentioned, somewhat deeper at the upper end than at the lower, but insofar as the generic invention is concerned this is not deemed absolutely essential.

In Fig. 12 a slight modification is shown, which while not advantageous for reasons which will be apparent, is illustrated to bring out the scope of the present invention. In said figure the tube is shown in cross section and is provided with but a single groove which extends nearly across the diameter of the tube. The outer edges of the groove, after it is formed in the cylindrical tubular member, will be brought together in a cylindrical forming die. This cylindrical forming die can, of course, be employed to close a plurality of grooves.

Under the various forms of the shaft as shown it is to be noted that there are no openings or perforations which might lead to initial fracture. The body of the shaft is of substantially the same thickness throughout, with the possible exception of the overlap seam portion, which is less than $\frac{3}{32}$ " in width.

In Fig. 1 I have shown a section of a golf head denoted by 14, which is secured to the

lower end of the shaft, suitable filling material 15 being placed in the grooves at the lower end of the shaft, and about said lower end a strip of leather or other suitable material, as 16, which will cause proper adhesion between the shaft and the head of the club, will be employed as set forth in my Patent No. 1,257,084, dated February 19, 1918. A portion of a grip surface, as 17, is also indicated in this figure.

It is to be understood that the term "wall" as employed in the annexed claims, is intended to and includes the walls of the groove or grooves and that portion or portions of the body intermediate said groove or grooves.

What is claimed is,—

1. As a new article of manufacture, a golf shaft formed as a tapering metallic tube having a plurality of grooves extending longitudinally thereof, the wall of the body of the shaft being of substantially the same thickness throughout its length.

2. As a new article of manufacture, a golf shaft formed as a tapering metallic tube, having at least one groove extending longitudinally thereof, the wall of the body of the shaft being substantially the same thickness throughout its length.

3. As a new article of manufacture, a golf shaft formed as a tapering metallic tube produced from sheet metal, the edges whereof are interlocked and brazed, the wall of the body of the shaft being of substantially the same thickness throughout its length and having a plurality of grooves extending longitudinally thereof.

4. As a new article of manufacture, a golf shaft formed as a seamless tapering metallic tube having a plurality of equally spaced grooves extending longitudinally thereof, the wall of the body of the shaft being of substantially the same thickness throughout its length and presenting an unbroken surface.

5. As a new article of manufacture, a golf shaft formed as a tapering metallic tube, having an overlapped seam, said tube having a plurality of equally spaced grooves extending longitudinally thereof to permit torsioning of the shaft under stress, the wall of the body of the shaft being of substantially the same thickness throughout its length.

6. As a new article of manufacture, a golf shaft formed as a tapering metallic tube of high carbon steel, the walls whereof throughout the entire body of the shaft have a thickness of substantially .012", the shaft likewise having at least one groove extending longitudinally thereof to permit torsioning of the shaft.

7. As a new article of manufacture, a golf shaft formed as a tapering metallic tube of high carbon steel, the walls whereof

throughout the entire body of the shaft have a thickness of substantially .012", the shaft likewise having a plurality of equally spaced grooves extending longitudinally thereof to 5 permit torsioning of the shaft.

8. As a new article of manufacture, a golf shaft formed as a tapering metallic tube having a plurality of grooves extending longitudinally thereof, the grooves at the 10 upper larger portion of the shaft being deeper than they are at the lower end of the shaft.

9. As a new article of manufacture, a golf shaft formed as a tapering metallic 15 tube having a plurality of equally spaced grooves extending longitudinally thereof to permit the shaft to torsion, the grooves being deepest at the upper end of the shaft and becoming gradually shallower toward 20 the lower end of the shaft.

10. As a new article of manufacture, a golf shaft formed as a tapering metallic tube, having three grooves extending longitudinally thereof and equi-distantly spaced 25 about the axis of the shaft.

11. As a new article of manufacture, a golf shaft formed as a tapering metallic tube having three grooves extending longitudinally thereof and equi-distantly spaced 30 about the axis of the shaft, said grooves being relatively deep at the upper end of the shaft and growing shallower toward the lower end thereof.

12. As a new article of manufacture, a golf shaft formed as a tapering tube produced from sheet steel, said tube being of substantially the same thickness throughout 35 and having at least one reentrant groove extending longitudinally thereof.

13. In combination with a shaft formed of a relatively thin walled metallic tube, said tube having grooves extending longitudinally thereof, and the upper end of the tube being slightly tapered; a tubular metallic handle fitting over such tapered end, the 40

lower end of the handle being reversely tapered to make a close fit with the upper end of the shaft; and filler pieces fitting within the grooves in the upper end of the shaft to prevent lateral movement thereof. 50

14. As a new article of manufacture, a golf shaft formed as a tapering metallic tube having an overlapped seam, said tube having a plurality of equally spaced grooves extending longitudinally thereof to permit 55 the shaft to torsion, the wall of the body of the shaft being of substantially the same thickness throughout its length.

15. As a new article of manufacture, a golf shaft formed as a tapering lapped jointed metallic tube of high carbon steel, the walls whereof, throughout the body of 60 the shaft, have a thickness of substantially .012", the shaft likewise having a plurality of equally spaced grooves extending longitudinally thereof to permit the shaft to torsion. 65

16. As a new article of manufacture, a golf shaft formed as a tapering metallic tube having a plurality of grooves extending 70 longitudinally thereof, the grooves at the upper larger portion of the shaft being deeper than they are at the lower end of the shaft, the grooves being of sufficient depth to permit a noticeable torsion in the 75 shaft.

17. As a new article of manufacture, a golf shaft formed as a tapering metallic tube produced from sheet metal, the edges 80 whereof are overlapped, a sheet of copper alloy being interposed between the overlapping portions, said edges being interlocked and brazed, said shaft having at least one groove extending longitudinally thereof throughout its length and of sufficient depth 85 to permit the shaft to torsion under impact.

In testimony whereof I have signed my name to this specification.

ALLAN E. LARD.
